STROBOSCOPE

Fritz Hamacher, Spandau-Ruhleben, Germany,
assignor to General Electric Company, a corporation of New York

Application May 4, 1936, Serial No. 77,880
In Germany May 24, 1935

13 Claims.

(Cl. 88—14)

My invention relates to stroboscopes and concerns particularly such apparatus for viewing very rapidly moving objects.

It is an object of my invention to provide means for producing light flashes having a very high order of frequency.

Other and further objects and advantages will become apparent as the description proceeds.

In accordance with my invention in its preferred form, I employ a cathode ray tube having a fluorescent screen and means for causing cathode rays to impinge on the fluorescent screen intermittently with a high frequency. The tube is so arranged that the fluorescent screen projects the light upon the rapidly moving object to be viewed or provides a luminous background for silhouetting the moving object.

The invention will be understood more readily from the following detailed description when considered in connection with the accompanying drawing and those features of the invention which are believed to be novel and patentable will be pointed out in the claims appended hereto. In the drawing, Fig. 1 is a schematic diagram representing one embodiment of my invention and Fig. 2 is a schematic diagram representing a modification of the apparatus of Fig. 1. Like reference characters are utilized in the drawing to designate like parts throughout.

In the arrangement of Fig. 1, an electronic tube 11 is employed having an evacuated envelope 12 containing a fluorescent screen 13 at one end and a cathode 14 at the other end for producing radiant energy, preferably cathode rays or electrons impinging upon the screen 13. The cathode 14 is preferably of the incandescent type having a source of current 15 for heating the cathode to incandescence. If an incandescent cathode is employed the envelope may be evacuated to approximately .001 micron. On the other hand with a cold cathode air pressures as high as 5 to 15 microns may be desirable. The tube 11 may be similar to the known cathode ray tubes or to Braun tubes but preferably the cathode 14 is of relatively increased size and the other electrodes are suitably arranged to produce a light source of relatively large area at the fluorescent screen 13 by having the cathode rays emerge in a divergent fan or cone-shaped bundle spread over substantially the entire surface of the screen 13. In addition to the cathode 14, an anode 16 is provided and preferably also a control electrode 17. In the arrangement of Fig. 1, the anode 16 and the control electrode 17 are in the form of perforated disks, diaphragms or cylinders and the spacial

arrangement between them and the relative voltage applied is such as to diverge the cathode rays emanating from the cathode 14.

The tube is energized by a source of current 18 connected between the cathode 14 and the anode 16. Suitable means are provided for interrupting the cathode rays intermittently in order to cause intermittent energization of the fluorescent screen 13, thereby producing light flashes for stroboscopic purposes. If desired, the interruption of the cathode rays may be produced by making the energizing current source 18 a source of alternating current.

In the arrangement of Fig. 1, I provide a voltage divider 19 connected between the terminals 15 of the current source 18 and connect the control electrode 17 to an intermediate point on the voltage divider 19. The relative voltages of the electrodes 16 and 17 are such as to spread the cathode rays into a cone or a solid angle covering the 20 screen 13. Inasmuch as the ratio of the instantaneous voltages applied to the control electrode and the anode 16 determines the focusing or degree of divergence of the cathode rays, it will be apparent that the focusing of the rays and the 25 illuminated area of the fluorescent screen 13 is unchanged by the variations in instantaneous value of the voltage of the source 18. It will be understood that, when the instantaneous value of the voltage falls below zero, or, in fact, below 30 a given positive value, the emission of cathode rays will be cut off and the screen 13 will become dark. The frequency of the light flashes produced by the fluorescent screen will, therefore, coincide with the frequency of the alternating-current 35 source 18.

The light produced by the fluorescent screen 13 is caused to illuminate a moving object which is to be observed. Such a moving object may, for example, be a rotating gear 20. If desired, the 40 brilliancy of the fluorescent screen 13 may be diminished by weakening the cathode rays and the rotating gear 20 may be observed by arranging the apparatus to bring the gear 20 between the fluorescent screen 13 and the observer's eye 45 21, thus silhouetting the gear 20 against the fluorescent screen 13. When used for silhouetting, the surface of the screen 13 is preferably of such area as to subtend as great an optical angle as the moving object to be observed, such as the gear 20 or one of the teeth thereof.

It will be understood that, in viewing moving objects stroboscopically, the object may be made to appear to stand still or to move very slowly by illuminating it with light flashes having the same 55

- frequency or a frequency nearly the same as that of the speed of revolution, speed of vibration, or in the case of gears and similar objects with repeated similar parts such as spokes or teeth the angular speed divided by the number of spokes, teeth, or other repeated parts. In order to adapt the apparatus for observation of parts moving at different speeds, it is desirable to employ means for varying the frequency of the light flashes.
- 10 For this purpose a suitable variable frequency alternating current source may be employed at 18, e. g. a variable frequency vacuum tube oscillator such as illustrated in Fig. 2.

Although I have found that satisfactory results may be obtained by utilizing an alternating current energizing source to produce the interruptions in the illumination of the fluorescent screen, it will be understood that my invention is not limited to this precise arrangement. My invention obviously includes other means for interrupting the energization of the fluorescent screen, such as means for causing cathode rays to sweep across the fluorescent screen or around a target protecting the screen, or means for interrupting the voltage applied to a control electrode.

For example, in the arrangement of Fig. 2, I have shown a cathode ray tube 11 having a cathode 14 and an anode 16 corresponding to the cathode and anode of the apparatus of Fig. 1 but energized by a direct-current source 22. The tube of Fig. 2 has two auxiliary electrodes which might be termed "control electrodes", one of which, the electrode 23, serves as a focusing electrode for controlling the focusing of the cathode rays and is connected to an intermediate tap of the direct-current source 22, and the other of which, in the form of a grid 24, is arranged to cut off the cathode rays in the usual manner by interposing a negative electrostatic field. The control electrode 24 may be utilized to produce intermittent illumination of the fluorescent screen 13 by connecting a variable frequency alternating-current source 25 between the cathode 14 and the control electrode 24. Cathode rays will be caused to impinge upon the fluorescent screen 13 with a frequency corresponding to the frequency of the variable frequency source 25 since, whenever the voltage of this source becomes negative, the cathode rays will be cut off. Inasmuch as stroboscopes employing cathode ray energized fluorescent screens are of particular value for observing extremely high frequency phenomena for the reason that cathode rays lend themselves to control at considerably higher frequencies than the frequencies of light flashes which have hitherto been available in stroboscopic apparatus, I prefer to provide a source of high frequency, such as a vacuum tube oscillator, for energizing the control electrode 24. Some portion of the vacuum tube oscillator circuits, such as an inductance or a condenser 26 may be made variable, and may be provided with a control handle extending from the casing of the oscillator 25 or with other suitable means to permit varying the frequency of the light flashes illuminating the moving object 20.

If desired, instead of actually interrupting cathode rays for the purpose of producing light flashes from the fluorescent screen 13, I may cause the cathode rays to sweep across the fluorescent screen 13. For example, by adding electromagnetic beam control means, such as a coil, or electrostatic beam control means, such as a pair of deflecting plates 27, energized by a suitable source of alternating current 28, I may cause the beam

to sweep back and forth across the fluorescent screen 13. Preferably, in this form, of the invention, the cathode 14 and the electrodes 23 and 24 are so shaped as to produce a flat beam in the form of a sheet of cathode rays in a plane perpendicular to the plane of the paper as seen in Fig. 2. The beam is thus fan shaped with the cathode rays spread across the solid angle which is subtended by the screen 13. By employing a fast fluorescent screen, such as one comprising calcium tungstate, the illumination of the screen will persist for a very short period of time after the cathode ray beam has passed across the screen and will be darkened in the interval between successive sweeps of the beam across the fluorescent screen 13.

If desired the sweep plates 27 may be so arranged in relation to the other electrodes that the cathode rays are swept beyond the fluorescent screen to insure intermittent cessation of illumination, or one or more targets 29 may be provided in one or more portions of the tube to intercept the cathode rays during a portion of each successive sweep.

I have herein shown and particularly described certain embodiments of my invention and certain methods of operation embraced therein for the purpose of explaining its principle and showing its application but it will be obvious to those skilled in the art that many modifications and variations are possible and I aim, therefore, to cover all such modifications and variations as fall within the scope of my invention which is defined in the appended claims.

What I claim as new and desire to secure by Letters Patent of the United States is:

1. In a silhouetting stroboscope, the combination of a cathode ray tube having a fluorescent screen, and means within the tube for producing cathode rays, spreading them across a solid angle covering the screen and producing impingement of said rays upon said screen intermittently at high frequency to form high frequency light flashes each extending over the area of said screen.

2. In a stroboscope for viewing rapidly moving objects, the combination of a cathode ray tube with a fluorescent screen for providing light, means for generating a divergent cone of cathode rays impinging on said screen and substantially covering it to cause it to produce light, and means for interrupting at a high frequency the impingement of cathode rays on said screen to cause the light thereof to occur in high-frequency flashes.

3. In a stroboscope for viewing rapidly moving objects, the combination of an electronic tube with a fluorescent screen for providing light, means within the tube for directing radiant energy against said fluorescent screen and spreading said radiant energy across substantially the entire surface of the screen to cause it to produce light over its area, and means for interrupting at a high frequency the impingement of radiant energy on said screen to cause the light thereof to occur in high-frequency flashes.

4. In a stroboscope for viewing rapidly moving objects, the combination of an electronic tube with a device for converting radiant energy into light, means within the tube for directing a divergent cone of radiant energy against said device with the base of said cone substantially covering said device to cause it to produce light, and means for interrupting at a high frequency the impingement of radiant energy on said device

to cause the light thereof to occur in high-frequency flashes.

5. In a stroboscope for viewing rapidly moving objects, the combination of an evacuated discharge tube containing a light-generating surface, and means also contained within the tube for simultaneously energizing substantially the entire area of said light generator with interruptions at high frequency.

10. 6. In a stroboscope for viewing rapidly moving objects, the combination of a cathode ray tube with a fluorescent screen for producing light, means for generating a fan-shaped bundle of cathode rays impinging on said screen and extending across its width to cause it to produce a line of light, and means for sweeping said cathode ray bundle transversely to itself across said screen beyond an edge thereof at high frequency to illuminate the entire screen and leave it dark alternately thus causing the light thereof to occur in high-frequency flashes.

7. In a stroboscope for viewing rapidly moving objects, the combination of a cathode ray tube with a fluorescent screen for providing light, means for generating a divergent cone of cathode rays impinging on said screen and substantially covering it to cause it to produce light, and means for interrupting said cathode rays at a high frequency.

8. In a stroboscope for viewing rapidly moving objects, the combination of a cathode ray tube with a fluorescent screen for providing light, an anode and a cathode, and a source of high-frequency alternating current directly connected between said electrodes.

35. 9. In a stroboscope for viewing rapidly moving objects, the combination of a cathode ray tube

with a fluorescent screen for providing light, an anode, a cathode and a beam cut-off control electrode, a source of high-tension current connected between said anode and cathode, and a source of high-frequency alternating current connected between said cathode and control electrode.

10. In a stroboscope for viewing rapidly moving objects, the combination of a cathode ray tube with a fluorescent screen for providing light, an anode, a cathode and a control electrode, a voltage divider, and a source of alternating current of high frequency connected to said anode and cathode and to said voltage divider, said control electrode being connected to an intermediate part of said voltage divider.

15. 11. In a stroboscope for viewing rapidly moving objects, the combination of a cathode ray tube with a fluorescent screen for providing light, an anode and a cathode, a source of variable frequency alternating current directly connected between said electrodes, and means for varying the frequency thereof.

12. In a stroboscope for viewing rapidly moving objects, the combination of a cathode ray tube having a fluorescent screen, means within the tube for producing a cathode ray beam extending across said screen and means for interrupting at high frequency impingement of said beam on said screen.

13. In a stroboscope arrangement for viewing rapidly moving objects, an evacuated discharge tube having a light generating surface, means contained within the tube for energizing intermittently at high frequency substantially the entire surface of said light generator simultaneously.

FRITZ HAMACHER.
